UNITED STATES PATENT OFFICE

SIMON HOFFMANN, OF KASSEL-WILHELMSHOHE, GERMANY, ASSIGNOR TO SCHMIDT'SCHE HEISSDAMPF-GESELLSCHAFT MIT BESCHRANKTER HAFTUNG, OF KASSEL-WILHELMSHOHE, GERMANY, A CORPORATION OF GERMANY

CYLINDRICAL MARINE BOILER WITH SUPERHEATER

Application filed July 31, 1928, Serial No. 296,616, and in Germany September 8, 1927.

My invention relates to improvements in cylindrical marine boilers with superheaters and one or more flame tubes or flues between the tubes which constitute or comprise the 5 furnace chambers and form the first gas path and the smoke tubes which lead to the chimney and form a third gas path of the boiler. The said tubes or flues between the furnace chamber and the smoke tubes form an intermediate or second hot gas passage. The hot 10 gases, therefore, flow through the boiler along three paths and in so doing make a twice repeated bend.

The object of my invention is an improved 15 boiler of this kind with two working pressures and superheaters for the high-pressure and the low-pressure part of the boiler. According to my invention, the superheater for the high-pressure part is arranged in the flue 20 forming the second path of the hot gases and the superheater for the low-pressure part is arranged in the second return chamber joining the intermediate flame tube or flue to the smoke tubes forming the third gas passage.

The advantage of the arrangement in accordance with my invention lies chiefly in the fact that higher superheats are obtained, i. e. 25 higher steam superheats, than is possible in the usual type of smoke tube superheater while the escaping gases are not cooled to such an extent that the boiler efficiency suffers. The hot gases are already cooled to such an extent in the first gas passage and in the first return chamber that there is no fear of the 30 burning of the superheater elements in the intermediate flame tube or flue while, on the other hand, the temperature of the hot gases is still sufficiently high to enable the desired degree of superheater to be obtained. Further 35 the efficient utilization of heat in the gases is independent of the degree of superheat because, after the gases have passed beyond the superheaters, there is a boiler heating surface which is approximately as large 40 as in the standard arrangement of smoke tubes in cylindrical marine boilers.

One embodiment of the invention is illustrated in the accompanying drawing in which Fig. 1 is a longitudinal section of a two- 45 pressure cylindrical marine boiler equipped

with steam superheating apparatus according to my invention and Fig. 2 is a transverse section on the line I—I of Figure 1.

The boiler as shown in the drawing has a low-pressure part formed by an usual smoke-tube boiler *b*, whilst the high pressure part is formed as an indirectly heated boiler. The generation of the high-pressure steam takes place in a steam-water drum 1 through a heat carrier (for instance, water and steam obtained therefrom), which passes its heat on the working boiler water in drum 1 through heating elements 2, which form part of a closed pipe system also comprising tubes 3 situated in the furnace chamber *a* of the boiler. The tubes 3, as shown, are also so disposed as to form a protection against heat for the wall of the first return chamber *e*.

These tubes 3 extend between the lower collecting chamber 4 and the upper distributing chambers 5. The latter are joined to the upper ends of the heating elements 2 through the uptake pipes 6, and the lower ends of the said heating elements 2 are joined to the collecting chamber or chambers 4 through downtake pipes 7. In two middle flame or smoke tubes *d*, *d*¹ which act as a flue extending between the first return chamber *e* from the furnace chamber *a* to the second return chamber *f*, are arranged the pipes *g* of the high pressure superheater. The steam from the high pressure boiler 1 is conducted to this superheater *g* through a transmission pipe *s* and the superheated steam is delivered from the superheater through the pipe *t*. The superheater *g*¹ for the low pressure boiler *b* is situated in the second return chamber *f* between the middle flame tubes *d*, *d*¹ and the tubes *b*¹ leading into the smoke box *c*. The steam from the low pressure boiler *b* is led to the superheater *g*¹ through a transmission pipe *s*¹, the superheated low pressure steam passing out from the superheater through the pipe *t*¹.

Having now particularly described and ascertained the nature of my said invention and in what manner the same is to be performed, I declare that what I claim is:

A cylindrical marine boiler with two working pressures and superheaters for the high-

pressure and the low-pressure part having a furnace chamber forming a first hot gas passage, a flue within the boiler forming a second gas passage, smoke tubes forming a third gas passage, a first return chamber between the first and the second gas passage, a second return chamber between the second and the third gas passage, a superheater for the high-pressure part of the boiler arranged in said second gas passage and a superheater for the low-pressure part of the boiler arranged in said second return chamber.

In testimony whereof I affix my signature.
SIMON HOFFMANN.
